UNITED STATES PATENT OFFICE.

MOSES A. MARTINDALE, OF ELKHART, INDIANA.

ROAD OR TRAMWAY FOR VEHICLES.

SPECIFICATION forming part of Letters Patent No. 315,047, dated April 7, 1885.

Application filed January 17, 1884. (No model.)

To all whom it may concern:

Be it known that I, MOSES A. MARTINDALE, of Elkhart, in the county of Elkhart and State of Indiana, have invented a new and useful Improvement in Roads or Tramways for Vehicles, of which the following is a full, clear, and exact description, reference being had to the annexed drawings, forming part of this specification.

10 This invention has for its object to provide for an easy and quick transportation of passengers, farm produce, and other freight by horse-power, steam, compressed air, electricity, gas, pedal or hand power on and over 15 the common wagon-roads to and from farms, towns, and cities, or wherever the demands of trade or business require a thoroughfare.

In the drawings, Figure 1 is a cross-section of my improved tramway. Fig. 2 is a section 20 of the same, showing modifications. Fig. 3 is a partial plan view, and Fig. 4 is a side elevation. Figs. 5, 6, and 7 are detail views of the rail-joint.

A indicates a metallic rail formed of a 25 flanged or trough-like plate, B, of any desired width or thickness, and the rail proper, C, which latter may be made in one piece with said plate, or may be bolted thereto, as shown in Figs. 1 and 2. The plate B has a 30 central horizontal portion, and a flange, D, at each side of said portion, which flanges incline outwardly from each other, so that when the rail A is inverted and the said flanges are embedded in the road-bed they 35 will brace each other against any lateral strain and prevent the rail from becoming displaced. The lower edges of the flanges D are turned out horizontally to form bases, to prevent them from sinking deeper in the

40 ground than desired, and to hold said edges in the same horizontal plane. The central portion, E, of the plate B serves as a track for wagons and such vehicles, and for such use may be employed, if desired, without the 45 rails proper, C. Where the rails proper are used, they are located at the outer edge of the central portion, E, so that the inner half of said portion may serve as a track for wagons, while the rails proper form a track for flange-wheeled vehicles and a guide for wagons. The 50 flanges D at their outer edges are also in-

clined horizontally outward in a plane parallel with that of the central portion, E, and the rails A of each side of the road are connected together by gage-bars F, which are 55 bolted to the said inclined edges of the said flanges. The gage-bars may reach only from the inner flange of one rail to that of the other, or they may extend also to the outer flanges of the rails and be bolted to each flange 60 of each rail.

The rails A are to be ballasted by any suitable material placed under them between the flanges D, while the space between the gage-bars F and the plane of the portions E is to be 65 filled with coarse gravel, cobble-stones, prepared concrete, or asphalt, or other paving material. The sides of the road outside the rails are to be built up with like material.

Where a tramway is built over soft or 70 marshy ground, the flanges D are to be increased in width by bolting to their lower edges on the inner side plates, G, which shall take a deeper hold upon the ground, and which are to be supported underneath by a 75 ballast of hardened concrete blocks, hewed stone, or sawed timbers.

The rails are connected together by double or interlocking lap-joints formed by beveled recesses H, having elongated bolt-holes I, to 80 allow for contraction and expansion. The central part, E, and both flanges D are each provided with a double joint, so arranged that the entire rail-joint shall consist of alternate overlapping and underlapping tongues or 85 parts, as clearly shown in Fig. 7. These tongues may be provided with elongated holes I, by which the rails may be connected together with bolts. These elongated holes are shown in Fig. 5. 90

What I claim is—

1. The combination, with the trough-shaped rails A and connecting gage-bars F, of the plates G, substantially as shown and described.
2. The trough-shaped rails A, having flanged plate B and beveled ends H, interlocking with each other, and elongated bolt-holes, substantially as shown and described. 95

MOSES A. MARTINDALE.
